ATTORNEY.

UNITED STATES PATENT OFFICE.

HANS H. SIEH AND CHRISTIAN HOLSTEIN, OF MILLARD, NEBRASKA.

POTATO-BUG DESTROYER.

SPECIFICATION forming part of Letters Patent No. 642,268, dated January 30, 1900.

Application filed August 11, 1898. Serial No. 688,386. (No model.)

To all whom it may concern:

Be it known that we, HANS H. SIEH and CHRISTIAN HOLSTEIN, residing at Millard, in the county of Douglas and State of Nebraska, have invented certain useful Improvements in Potato-Bug Destroyers; and we do hereby declare that the following is a full, clear, and exact description of the invention, such as will enable others skilled in the art to which it appertains to make and use the same, reference being had to the accompanying drawings, which form a part of this specification.

This invention has relation to a new and novel improvement in potato-bug crushers.

The object of our invention is to provide a device which will be adapted to be carried through a potato-patch and be arranged to brush and knock off the potato-bugs, which are thrown into the receptacle, at the bottom of which they collect and where they are crushed and killed, the remains dropping through the rollers to the ground.

In the accompanying drawings we have shown in Figure 1 a top view of a potato-bug crusher embodying our invention, while Fig. 2 shows an under view, with portions broken away, of a potato-bug crusher embodying our invention.

Our device embodies, essentially, an axle A, of any suitable size and preferably round, to which axles are secured ordinary wheels 22 and from which axle A extends the tongue 3, to which the draft-animal is secured. The tongue 3 is strengthened by means of the transverse bars 4, as will be noticed in referring to Fig. 1. Working upon the axle A and revolving with the same is a sliding clutch-collar 15, which clutch-collar can be thrown backward and forward by means of an ordinary operating-lever 17, which by means of a pin 18 is secured to an ordinary supporting-bracket 16, extending from the rear transverse brace 4 and riding upon the axle A, as is shown.

Loosely working upon the shaft A is a clutch-collar 14, provided with a sprocket-wheel, from which extends a chain 13, which chain in turn works over a sprocket-wheel 12, which pulley forms part of a stub-shaft 11, which stub-shaft is held within a bracket 29, forming part of rear depending vertical bar 5, as is clearly shown in Fig. 3. This

bar 5 is secured to the bar 4 and is additionally supported by means of an ordinary stay-rod 19. Mounted upon the opposite end 55 of the stub-shaft 11 is an ordinary bevel-gear 10, which bevel-gear meshes with a second bevel-gear 9, which bevel-gear 9 is secured to a shaft 6, which works through the vertical bars 55 and is provided with a hub 60 7, from which hub extend the reeds or switches 8 8. Now should it be desired to revolve these reeds or switches 8 while the vehicle is being carried forward it would simply be necessary to throw in the clutch 15 to 65 engage the clutch 14, so that the rotary movement of the shaft A would be imparted to the stub-shaft 11 and through the gears to the reeds 8.

Opposite to the point where the reeds-supporting hub 7 is in position is a receptacle B, provided with the back 20 and a bottom 21, a portion of which bottom 21 is opened, as is shown in Fig. 1, and within this opening are held two ordinary crushing-rollers 23 and 24, 75 one being provided with a shaft 27 and the other with a shaft 22, as is shown in Fig. 2. These rollers are made to revolve toward one another by means of the meshing gears 25 and 26. Secured to the shaft 27 is an ordinary pulley 28, over which the ordinary belt 30 passes, which belt 30 at the other end passes over pulley 31, mounted upon shaft 6, supporting the bevel-gear 9, as is shown, so that as the brush is revolved the rollers are 85 also turned, so that the bugs as they are brushed off of the potato-vines, which vines are adapted to come out at a point approximately below the brushes or reeds 8, will be swept off and into the receptacle B, where 90 they will be crushed by the rollers.

The device is light and readily operated, and,

Having thus described our said invention, what we claim as new, and desire to secure by 95 Letters Patent, is—

The combination with a suitable supporting-frame, of a wheel-rotated supporting-axle, a sliding clutch working upon said axle, a suitably-supported lever to operate said clutch, a rotating counterpart-clutch loosely mounted upon said axle, provided with a sprocket-wheel, a suitably-supported stub-shaft, a sprocket-wheel and bevel-gear upon

said stub-shaft, a chain connecting said stub-shaft sprocket to said clutch-sprocket, a brush-shaft suitably supported, a bevel-gear secured to said brush-shaft and meshing with 5 said stub-shaft gear, a plurality of reeds or brushes extending from said brush-shaft, a depending receptacle positioned below and adjacent to said reed-provided shaft, crushing-rolls within said receptacle, and belt connection between said crushing-rolls and said

brush-shaft, all arranged substantially as and for the purpose set forth.

In testimony whereof we affix our signatures in the presence of two witnesses.

HANS H. SIEH.
CHRISTIAN HOLSTEIN.
